US0D1049599S

(12) **United States Design Patent** (10) **Patent No.:** **US D1,049,599 S**
(45) **Date of Patent:** **** Nov. 5, 2024**

(54) **PAIR OF SHOE INSOLES**

(71) Applicant: **Mark V. Dentler**, Conyers, GA (US)

(72) Inventor: **Mark V. Dentler**, Conyers, GA (US)

(**) Term: **15 Years**

(21) Appl. No.: **29/866,244**

(22) Filed: **Sep. 2, 2022**

(51) LOC (14) Cl. **02-04**

(52) U.S. Cl.

USPC **D2/961**; D24/192

(58) **Field of Classification Search**

USPC D2/915, 946, 947, 949, 968, 976,
D2/951-961; D24/192

CPC A43B 19/00; A43B 7/00; A43B 3/00

(57) **CLAIM**

The ornamental design for a pair of shoe insoles, as shown and described.

DESCRIPTION

FIG. 1 is a front elevational view showing a pair of shoe insoles of my new design;

FIG. 2 is a bottom plan view thereof;

FIG. 3 is a top plan view thereof;

FIG. 4 is a right elevational view, the left elevational view being identical thereof;

FIG. 5 is a top front prospective view of the right insole thereof;

FIG. 6 is a rear bottom prospective view of the right insole thereof; and,

FIG. 7 is a rear elevational view thereof.

1 Claim, 7 Drawing Sheets
